UNITED STATES PATENT OFFICE.

HENRY B. SOMMER, OF PHILADELPHIA, PENNSYLVANIA.

DESIGN FOR A WATCH DISPLAY-CASE.

SPECIFICATION forming part of Design No. 16,927, dated October 5, 1886.

Application filed August 19, 1886. Serial No. 211,349. Term of patent 3½ years.

To all whom it may concern:

Be it known that I, HENRY B. SOMMER, a citizen of the United States, residing in the city and county of Philadelphia, State of Pennsylvania, have invented and produced a new and original Design for a Watch Display-Case, of which the following is a specification, reference being had to the accompanying drawings, forming part thereof.

10 The leading feature of my design for watch display-cases is the body of the case having fluffy sides and a top with beveled edges and a surrounding rim.

15 Figure 1 represents a perspective view of the watch display-case in a closed condition, and Fig. 2 represents a perspective view of the same in open condition.

A represents the body of a watch display-case, consisting of a base, B, and lid C. The top part, D, of the lid has sloping or beveled edges E, which are contiguous to the outer rim, F, of the lid. The sides of the base and lid, including the rim F, are fluffy, the whole presenting an attractive appearance.

I claim—

25 A design for a watch display-case, consisting of the base B and the lid C, with a top part, D, having beveled edges, and rim F, the sides of the base and lid being fluffy, as shown and described.

HENRY B. SOMMER.
